UNITED STATES PATENT OFFICE.

FREDERICK SEABERG, OF CHICAGO, ILLINOIS, ASSIGNOR, BY MESNE ASSIGNMENTS,
TO NATIONAL DUMP CAR COMPANY, OF CHICAGO, ILLINOIS, A CORPORATION OF
MAINE.

ORE-CAR.

1,035,389.

Specification of Letters Patent   Patented Aug. 13, 1912.

Application filed January 12, 1909. Serial No. 471,835.

To all whom it may concern:

Be it known that I, FREDERICK SEABERG, a citizen of the United States, residing at Chicago, in the county of Cook and State 5 of Illinois, have invented certain new and useful Improvements in Ore-Cars, of which the following is a specification.

The object of my invention is to provide a dump car of improved form adapted for 10 transportation of ore and other material.

The invention is more particularly directed to the dump door operating mechanism and the location and housing of the operating parts.

15 The particular nature of the invention will more clearly appear from the following description and claims, taken in connection with the accompanying drawings forming part of this application, in which—

20 Figure 1 is an end view of a car constructed according to my invention. Fig. 2 is a transverse section at the center of the car. Fig. 3 is a detail view of a shaft supporting bracket forming part of the structure illustrated. Fig. 4 is a side elevation of the car. Fig. 5 is a plan view of the car. Fig. 6 is a fragmentary side elevation of part of the door and that part of the operating mechanism adjacent thereto. Fig. 7 is a detail 25 view showing the connection of the door to a part of the operating mechanism, a part of the structure being shown in section on the line 7, 7 of Fig. 8, and Fig. 8 is a detail view in transverse section, showing the operating mechanism in several different positions.

The car illustrated in the drawings is primarily designed for transporting ore, but the operating mechanism shown and described in connection therewith may be used 40 in connection with cars of other type and used for other purposes. The ore car illustrated has vertical sides 1 reinforced upon the outside by angle irons 2, and inclined 45 ends 3, the sides and ends being reinforced at the top by angle irons 4.

The underframe of the car comprises a center sill made up in the present instance of channels 5 connected at the top and bottom 50 by plates 6, and bolsters 7. Rising from the ends of the bolsters are posts or pedestals 8 which support the ends of the plate girder sides 1. Extending longitudinally of the sides of the car are channels 9 having 55 their flanges directed outward and their up-

per surface about even with the upper surface of the channels 5 forming the center sill. The channels 9, however, are of less depth than the channels 5. In the present instance, the sheets 10 forming the plate 60 girder sides extend to about the level of the bottom of the center sill channels 5. The parts 11 of the sheets 10 which project below the channels 9 are turned outwardly and downwardly, forming a rectangular recess 65 12 designed to receive and form a tight joint with the outer edges of the door 13.

Extending from the end sills 14 to the side channels 9 are gusset plates 15, and a diagonal brace 16 extends from each of these 70 gusset plates to the bolster. A gusset plate 18 is secured at each corner of the car to the side sill 9, the corner post 20 and the pedestal 8, and extending from said gusset plate to the side plate of the car body is a diagonal 75 brace 21.

The doors 13 are hinged to brackets 22 secured to the webs of the channels 5 at such a height that in their closed position the doors have a slight incline downward 80 toward the car sides. The main power shaft 26 for operating the doors is mounted in bearings 24 just above the center of and supported by the center sill. The bearings 24, as shown in Fig. 6, are secured to angles 25, 85 which in turn are riveted to the top plates of the center sill. In order to protect the operating shaft 26 and the door hinges from becoming clogged with the contents of the car, I cover these parts with a housing which 90 consists of plates 27 which slope downwardly from a longitudinal line above the center of the center sill to the top edges thereof, and then downwardly at a less angle to a point just above the doors when in their closed 95 position. As shown in Fig. 6, the plates 27 are supported from the center sill by means of plates 28 which are secured to the top plates of the center sill by means of angles 29. The cover plates 27 are secured to the 100 supporting plates 28 by means of angles 23. Above the meeting edges of the plates 27 is a ridge 30 taking the form of an angle, the apex of which lies along the center of the car with the webs lapping over and secured to the cover plates 27. A counter shaft 32 located beneath the main operating shaft 26 is supported in bearings 33 which in turn are supported by hangers 34 depending from the center sill. As shown in Fig. 110

3, the hangers 34 have approximately the form of a letter U, the legs of which are riveted to the inside of the center sill channels 5. The bend of the U is made concave,—as shown at 36—and a strap 37 cooperates with the bend 36 to form a seat for the bearing 33. The main operating shaft 26 extends through to one end of the car, and upon its projecting end two star wheels 35 and 36 are secured. The outer star wheel 36 is operated by a reversible pawl 37 mounted upon the operating handle 38, and by means of said operating handle and pawl, the shaft 26 may be turned in either direction. Coöperating with the inner star wheel 35 is an escapement lever 40 having a pallet end 44, whereby under the rotative force imparted to shaft 26 by the falling doors, said shaft may be given a gradual step by step movement in order to ease the shock of the falling doors. Secured to the inner end of the shaft 26 is an operating chain 42 which at its opposite end is secured to a drum 43 fixedly mounted upon the counter shaft 32, the diameter of the drum 43 being greater than that of the shaft 26 for the purpose of reducing the amount of force necessary to operate the doors.

Depending from the body of the car at each side of each of the dump doors are pivoted hanger links 45. As shown in Figs. 4, 7 and 8, these links are hung upon pivots 46 extending outward from the vertically downturned edge portion of the end plates 3. The pivots 46 are further supported by hangers 48 riveted to the outside of the inclined part of said plates 3 and engaging said pivot at a point intermediate the two members of which each hanger link 45 is composed. Each member of each of the hanger links 45 is provided at top and bottom with an inwardly projecting hub 50 for the purpose of spacing the members apart in order that they may receive between them the rocker arm or lever 51.

The levers 51 in the present instance are constructed in the form of sectors or segmental sheaves, and are pivoted at one end of the arcuate portion to a pin 52 extending therethrough and through the lower ends of the members of the hanger 45. Secured to one of the straight sides of the segmental sheave or sector lever 51 by means of an eye bolt 53^a adjustably attached to the apertured lug 51^a by nuts 51^b, 51^c is a chain 53 secured at its opposite end to the counter shaft 32. At the angle between the straight sides of the sector lever, said lever is pivoted to the Z-bar 55 depending from the dump door. As clearly shown in Figs. 4 and 7, the pivot pin 56 is flattened at one end and riveted to said Z-bar 55, and a cotter pin 57 serves to hold the segmental sheave or lever 51 in place upon the pivot 56. The pivots 56 may, however, be formed

upon the opposite ends of a bar extending continuously across the door and fastened thereto. As will be apparent from an inspection of Figs. 4, 6 and 7, the hanger levers 45 and segmental sheave or lever 51 are located outside of the range of movement of the dump door and are, therefore, free to swing to the positions illustrated in Fig. 8.

Referring to Figs. 1 and 2, it will be apparent that the unwinding of the chain 42 from the shaft 26 will permit the counter shaft 32 to rotate in clockwise direction, thus allowing the door chains 53 to unwind under the weight of the doors and the load thereon. When the doors are in closed position as illustrated in Figs. 1 and 2, their weight and that of the load acting vertically downward upon the pivots 56 will have a tendency to rotate the segmental sheaves or levers 51 outwardly toward the sides of the car. Owing, however, to the fact that when the doors are closed each of the pivots 56 lies not far from the vertical line extending through the pivots 52, the component of the weight of the doors and load acting to throw the segmental sheaves or links 51 outward will not be large. The parts are so proportioned, however, that this component will be sufficient to start the opening movement of the doors, but not sufficient to impose any greater strain upon the door operating chains 53 and 42 even when the car is loaded. The downward force acting upon the segmental sheaves or links 51 through the pivots 56 will communicate an inward thrust upon the pivots 52 at the lower ends of the hanger links 45, and due to this inward thrust the parts will assume the position designated in Fig. 8 by the letter A, this being the position assumed when the doors are a little less than half opened. A continuation of the opening movement draws the hanger link outward again, and when the door is in its fully opened position, the parts occupy the position designated in Fig. 8 by the letter B.

In closing the doors by rotating the main shaft 26 in counter clockwise direction by means of the operating lever 48, the operation of the parts will be as follows: Referring to Fig. 8, and assuming the door is in its wide open position, as designated by the reference numerals, having the letter B applied thereto, the first effect of tension upon the chain 53 due to rotation of the main shaft 26 will be to effect a toggle action, the arms of the toggle being the hanger link 45 and the part of the segmental sheave or lever 51 in alinement therewith, the power being applied at the elbow 52^b or joint of the toggle. As the movement progresses, the amount of the toggle action will decrease and the segmental sheave or lever 51 will begin to rotate upon its axis 52, exercising a simple lever action upon the door through

the pivot 56. It will be apparent that in the position of the parts designated by the letter B in Fig. 8, when power is first applied to close the door it acts upon the mechanism 5 considered as a toggle, power being applied in the most advantageous manner, that is, at the elbow thereof; but in this position of the parts, the power exercised through the chain 53 has but little efficiency in its application to the segmental sheave or lever 51 10 considered as a simple lever, for the reason that the power is applied almost at the fulcrum of the part 51 considered as a simple lever. As the movement progresses, however, the arcuate edge of the segmental sheave or lever 51 thrusts the chain upward away from the pivot 52, thus progressively increasing the advantage of the power applied to the part 51 as a simple lever. This 15 increase in the length of the power arm continues through the closing movement until when the door has almost reached the closed position, the length of the lever arm is greatest and is equal to a straight line joining the 20 angles of the lever at the ends of its arcuate side.

By means of the mechanism above described, a most efficient door operating mechanism is provided, one in which, at the beginning of the closing movement, power is advantageously applied to a toggle, after which one of the members of the toggle is utilized as a simple lever with gradual increase of power arm, which increase of 25 length reaches its maximum when the door reaches its closed position and encounters the greatest resistance due to any obstruction which may be in the way and to the necessity of bringing the door tightly against 30 the adjoining fixed parts of the car body. The mechanism possesses the further advantage of having its parts so arranged that in the closed position of the doors only a slight component of the weight of the doors and 35 load acts to cause tension upon the operating chains.

I would have it understood that I do not desire to limit myself to the precise construction and arrangement of parts shown 40 in the drawings and herein described, as various modifications or alterations may be made without departing from my original invention.

I claim:

1. In a car of the class described, a door, a hanger link pivoted to the car structure adjacent said door, an intermediate member pivoted to said link and having a part engaging said door, and means for moving 45 said intermediate member from a position where its pivotal connection to said hanger link lies between the pivotal connection of said hanger link and car structure and the point of engagement between said intermediate member and door, to a position where

the point of engagement of said intermediate member and door lies between the pivotal connections of said hanger link with said car structure and said intermediate member.

2. In a car of the class described, a door, a hanger link pivoted to the car structure adjacent said door, an intermediate member pivoted to said link and having a part engaging said door, and a chain and winding mechanism for moving said intermediate member from a position where its pivotal connection to said hanger link lies between the pivotal connection of said hanger link and car structure and the point of engagement between said intermediate member and door, to a position where the point of engagement of said intermediate member and door lies between the pivotal connections of said hanger link with said car structure and said intermediate member.

3. In a car of the class described, a dump door, a link pivoted to the car structure adjacent said door, a lever pivoted to the free end of said link and having a part engaging said door, means for actuating said lever to close said door, the parts being so disposed and proportioned that as the door approaches its closed position the point of engagement between said lever and door approaches the straight line between the pivots connecting said link to the car structure and to said lever, and in the closed position of the door rests adjacent said line.

4. In a car of the class described, a dump door, a link pivoted to the car structure adjacent said door, a lever pivoted to the free end of said link and having a part engaging said door, a chain and winding mechanism for actuating said lever to close said door, the parts being so disposed and proportioned that as the door approaches its closed position the point of engagement between said lever and door approaches the straight line between the pivots connecting said link to the car structure and to said lever, and in the closed position of the door rests adjacent said line.

5. In a car of the class described, a dump door hinged to the car structure, a depending link pivoted to the car structure adjacent the door, a lever pivoted to the free end of said link and having a part engaging said door, a winding shaft, a chain connecting said lever and winding shaft and adjustably attached to said lever, and means for rotating said shaft.

6. In a car of the class described, a hinged door, a link pivoted to the car structure adjacent said door, a lever pivoted to the free end of said link and to said door, and a winding shaft and winding chain operatively connected to said lever, said lever being provided with a bearing surface for said chain, said bearing surface being of such

form that when said link and lever are in alignment power is applied substantially at their pivotal connection to cause them to operate as a toggle, after which power is applied to said lever with gradually increasing advantage to rotate it upon its pivotal connection with said link.

7. In a car of the class described, a hinged drop door, a depending link pivoted to the car structure adjacent the free edge of said door, an intermediate link pivoted to the free end of said depending link and to said door near its free edge, a winding shaft adjacent the hinged edge of said door, a chain connecting said winding shaft and said intermediate lever, said intermediate link being provided with a bearing surface for said chain to govern the point of application of power thereto during its movement to close said door.

8. In a car of the class described, a hinged drop door, a depending link adjacent the free edge thereof and having its free end below the plane of said door when in closed position, an intermediate link pivoted to the free end of said depending link and to said door, said intermediate link inclining upwardly and outwardly from its pivot toward the free edge of said door, when the latter is in closed position, a winding shaft adjacent the hinged edge of said door, and a chain connecting said winding shaft and intermediate link.

9. In a car of the class described, a hinged drop door, a depending link adjacent the free edge thereof and having its free end below the plane of said door when in closed position, an intermediate link pivoted to the free end of said depending link and to said door, said intermediate link inclining upwardly and outwardly from its pivot toward the free edge of said door when the latter is in closed position, a winding shaft adjacent the hinged edge of said door, and a chain connecting said winding shaft and intermediate link, said intermediate link being provided with a bearing surface for said chain.

10. In a car of the class described, a hinged dump door, a depending link pivoted to the car structure adjacent to said door, and a triangular link pivoted at one angle to the free end of said depending link and at another angle to said door, said triangular link being provided with a chain bearing surface extending from its third angle to the angle where it is pivoted to said depending link.

11. In a car of the class described, a power shaft, a counter shaft, a drum on said counter shaft of greater diameter than either of said shafts, a chain connected to said power shaft and drum, a dump door, a depending link pivoted to the car structure adjacent said dump door, an operating

link pivoted to said depending link and to said door, and a chain secured to said operating link and to said counter shaft.

12. In a car of the class described, a power shaft, a counter shaft, a drum on said counter shaft of greater diameter than either of said shafts, a chain connected to said power shaft and drum, a dump door, a depending link pivoted to the car structure adjacent said dump door, an operating link pivoted to said depending link and to said door, and a chain secured to said operating link and to said counter shaft, said operating link being provided with a bearing surface for said chain.

13. In a car of the class described, a power shaft journaled adjacent the longitudinal median plane and extending inward from the end thereof, a counter shaft adjacent the longitudinal median plane of the car and below the power shaft, a drum on said counter shaft, a chain secured to said power shaft and drum, dump doors hinged at each side of the longitudinal center of the car, depending links pivoted to the car structure adjacent said doors, operating links pivoted to said depending links and to said doors, and chains secured to said operating links and to said counter shaft.

14. In a car of the class described, a center sill, a housing extending downwardly and outwardly from a longitudinal line above said center sill, dump doors hinged to said center sill beneath said housing, depending links pivoted to the car structure adjacent the sides of said doors, operating links pivoted to said depending links and to said doors adjacent their free edges, a shaft adjacent the longitudinal center of the car, chains secured to said shaft and to said operating links, and means for rotating said shaft.

15. In a car of the class described, a center sill, a housing extending downwardly and outwardly from a longitudinal line above said center sill, dump doors hinged to said center sill beneath said housing, depending links pivoted to the car structure adjacent the sides of said doors, operating links pivoted to said depending links and to said doors adjacent their free edges, a power shaft extending longitudinally beneath said housing, a counter shaft beneath said power shaft, a chain connected to said power and counter shafts and chains connected respectively to said counter shaft and said operating links.

16. In a car of the class described, dump doors, links pivoted to the car structure adjacent said doors, operating links pivoted to said depending links and engaging said doors, a chain adjustably secured to each of said operating links, and winding mechanism for said chain.

17. In a car of the class described, dump doors, links pivoted to the car structure adjacent said doors, operating links pivoted to said depending links and engaging said doors, a chain secured to each of said operating links, said operating link being provided with a bearing surface for said chain, and winding mechanism for said chain.
18. In a car of the class described, a dump door, operating connections between the car body and said door, each of said operating connections comprising a plurality of links, means for applying force to said links at their pivotal connection to cause them to act as a toggle and for applying force to one of said links to cause it to act as a simple lever.
19. In a car of the class described, a dump door, a segmental sheave mounted on said door and pivotally supported by the car structure at a point removed from its attachment to said door, and means for causing rotation of said sheave whereby said door may be raised.
20. In a car of the class described, a dump door, a segmental sheave mounted on said door and pivotally supported by the car structure at a point removed from its attachment to said door, and a flexible member adapted to wind on said sheave and cause rotation thereof whereby said door may be raised.
21. In a car of the class described, a dump door, a segmental sheave pivotally attached to said door, a depending link pivotally attached to the car structure and also pivotally attached to said sheave at a point removed from the pivotal attachment of said sheave to said door, and means for causing rotation of said sheave.
22. In a car of the class described, a dump door, a segmental sheave mounted on said door, a movable supporting pivot for said sheave attached thereto at a point removed from the point of attachment to said door, and means for causing rotation of said sheave.
23. In a car of the class described, a dump door, a depending link pivotally attached to the car structure, a second link pivotally attached to said depending link at one end and to said door at the other end, said links being adjacent when said door is closed and in alinement when said door is open, and means attached to said second link and independent of said depending link for causing a movement of said second link from its position in alinement with said depending link to its position adjacent said link.
24. In a car of the class described, a dump door, a depending link pivotally attached to the car structure, a second link pivotally attached to said depending link at one end and to said door at the other end, said links being adjacent when said door is closed and in alinement when said door is open, and means attached to said second link and independent of said depending link for causing a movement of said second link from its position in alinement with said depending link to its position adjacent said link.
25. In a car of the class described, a dump door, two freely moving links, one being pivotally attached to the car structure at one end, the other being pivotally attached to the door at one end adjacent said first named link to hold said door closed, said links being pivoted to each other at their opposite ends, and means adapted to wind upon said second named link for normally holding said second named link in its door holding position, said means being also adapted to move said link to said position.
26. In a car of the class described, a dump door, a depending link pivotally attached to the car structure, an intermediate member having a part engaging said door and pivoted to said link at a point removed from its engagement with said door, said member being adapted by its rotation to raise said door to a closed position, and means adapted to wind upon said member for applying a rotating force to said member.
27. In a car of the class described, a dump door, a depending link pivotally attached to the car structure, an intermediate member having a part engaging said door and pivoted to said link at a point removed from its engagement with said door, said member being adapted by its rotation to raise said door to a closed position, and a flexible member adapted to wind upon said intermediate member and impart a rotating force to said intermediate member.
28. In a car of the class described, a dump door, a depending link pivotally attached to the car structure, an intermediate member having a part engaging said door and pivoted to said link at a point removed from its engagement with said door, said member being adapted by its rotation to raise said door to a closed position, a flexible member adapted to wind upon said intermediate member and impart a rotating force to said intermediate member, and means for taking up the slack of said flexible member.
- In testimony whereof, I have subscribed my name.
